Alvin M. Cohan, North Bergen, N. J., assignor to
The Eagle Manufacturing Company, Union
City, N. J., a corporation of New Jersey

Application August 4, 1947, Serial No. 140,684

Term of patent 14 years

(Cl. D15—1)

To all whom it may concern:

Be it known that I, Alvin M. Cohan, a citizen of the United States, residing at North Bergen, in the county of Hudson and State of New Jersey, have invented a new, original, and ornamental Design for a Reclining Garden Chair, of which the following is a specification, reference being had to the accompanying drawing, forming part thereof.

I claim:

The ornamental design for a reclining garden chair, substantially as shown.

ALVIN M. COHAN.
